UNITED STATES PATENT OFFICE.

ROBERT MIEHLE, OF CHICAGO, ILLINOIS.

TRIPPING MECHANISM FOR PRINTING-PRESSES.

1,300,288.

Specification of Letters Patent. Patented Apr. 15, 1919.

Application filed March 28, 1917. Serial No. 157,979.

To all whom it may concern:

Be it known that I, ROBERT MIEHLE, citizen of the United States, residing at Chicago, in the county of Cook and State of Illinois, have invented a certain new and useful Improvement in Tripping Mechanisms for Printing-Presses, of which the following is a full, clear, concise, and exact description.

- 10 My invention relates to tripping mechanisms for printing presses having particular relation to tripping mechanisms for rotary printing presses or presses in which, during the normal operation thereof, the impression elements are not moved out of and restored back into impression relation during each cycle of operation, and has for one of its objects to provide an improved press actuated mechanism for tripping and restoring the impression elements of the press which is adapted to perform its functions in a very efficient manner, the mechanism being so designed that the movable impression member, or cylinder, is within the complete control of the press actuated mechanism at all times during the movement of the impression element out of and into impression or printing position whereby all shock or chattering of the mechanism which might result from the impression element and its related mechanism moving ahead of the press actuated mechanism of its own accord, is prevented. This press actuated mechanism is complemented by a novel controlling mechanism adapted to allow the press actuated mechanism to assume complete control of the movements of the impression member out of and into impression position, as above described.
- 40 Inasmuch as the press actuated means functions to trip and to restore in succession and in order that the same may keep complete control of the impression element as it is tripped and restored I have designed the mechanism so that the controlling mechanism operates upon the tripping elements and restoring elements of the press actuated mechanism to render them functionless at different times whereby each of said elements is allowed to assume operative position and function to and retain the impression element in timed relation with the opposite or restoring element during all times in which the impression element is being moved out of or into printing position.

Another object resides in providing a sin-

gle revolution cylinder having a press actuated mechanism of the above described character adapted to trip and restore the cylinder in the same revolution in which it is tripped, the controlling mechanism having separate connection with the press actuated mechanism for controlling the tripping and restoring functions of the same, whereby the cylinder may be tripped for a single impression and restored to printing position in the same revolution in which it was tripped, or may be tripped for a succession of impressions, without being restored for a portion of each cycle, the press actuated mechanism acting in either case as above described. To render the controlling mechanism easy to operate, it embraces a single mechanism, which, when in one position, is adapted to be engaged by the press actuated means to render the same inoperative to trip, and, when in another position, is adapted to be engaged by said press actuated means to render the same functionless to restore.

80 A further object resides in providing a printing cylinder, a complemental impression cylinder, inking mechanism for the printing cylinder substantially out of inking relation with said printing cylinder when it is in the position it assumes when it is tripped, and tripping mechanism for the printing cylinder, the printing cylinder having a blank portion and the tripping mechanism being so timed that said blank portion is passing the engaging points of the impression cylinder and the inking mechanism with the printing cylinder when the cylinder is being moved out of and into printing position whereby the printing surface is inked but once for every impression regardless of whether or not the printing cylinder was tripped previously to the impression.

95 A further object resides in providing a printing cylinder and tripping mechanism therefor together with inking mechanism and a complemental impression cylinder in an improved interrelation which, by reason of the fact that such interrelation allows sufficient time for all of the elements to properly perform their functions, may do so in a very efficient manner and allow the other supplemental mechanisms of the machine to perform theirs in a like manner.

110 My invention has other characteristics and the invention in all of its aspects will be

fully described by reference to the accompanying drawings showing the preferred embodiment thereof and in which Figure 1 is a view in side elevation, parts broken away, of a portion of a printing press equipped in accordance with the invention; Fig. 2 is an end view illustrating the arrangement of gearing and cylinders which is preferred; Fig. 3 is a sectional elevation illustrating parts that are disclosed in Figs. 1 and 2 and other parts in addition, the printing and impression cylinders being out of printing relation; Fig. 4 is a view similar to Fig. 3 excepting that the printing cylinder is in printing relation; and Fig. 5 is a view in end elevation, with parts in section, of the tripping cam mechanism.

The power for operating the press is derived from a driving shaft 1 upon which there is a driving spur pinion 2 upon one side and near one end of the press. This spur pinion meshes with a spur gear 3 fixed upon a stub shaft 4 mounted in the extension 5 bolted to the base of the press frame. The spur gear 3 meshes with a spur gear 6 mounted freely upon a shaft 7 upon which shaft the impression cylinder 8 is fixed. The shaft 7 is journaled in boxes 7¹ that are contained in housings in the side frames of the press. These boxes are normally fixed to give a fixed axis of rotation of the impression cylinder 8 but are vertically adjustable by means of the adjusting screws 7². The gear 9 is fixed upon shaft 7 and meshes with a spur gear 10 which is fixed upon a stub shaft 11 journaled in the extension 12 bolted to the base of the press frame. The spur gear 10¹ is co-axial with the spur gear 10 and is also fixed upon the stub shaft 11 by being bolted to the gear 10 with bolts 11¹. The spur gear 10¹ is in mesh with a spur gear 10² fixed with respect to the spur gear 6 by being fixedly mounted upon the hub 6¹ of this latter gear. This hub 6¹ is journaled in a vertically adjustable bracket 12¹ carried upon the extension 12. This gear 10 is a cylinder gear mounted at an end of the printing cylinder 13 but not in fixed relation to the shaft 14 of this cylinder 13. The cylinder shaft 14 is journaled in boxes 15 that are mounted for vertical movement between guides 16 upon the press frame 17, the vertically movable boxes permitting movement of the printing cylinder transversely to the axis of the cylinder gear 10 and the axis of the cylinders 8 and 13. The distance between the axes of the gears 9 and 10 is fixed as their shafts 7 and 11 have fixed axes of rotation. As the printing cylinder 13 is adjustable with respect to the axis of its cylinder gear 10 flexible means are employed for connecting said cylinder gear 10 to cylinder 13. This flexible means preferably includes a unison ring or member 18 in the form of a disk which permits the axis

of the cylinder gear 10 to remain fixed while the axis of the cylinder may shift, this disk or connecting means 18 being shiftable with respect to said cylinder 13 and said cylinder gear 10. The disk 18 carries two diametrically opposite slotted guideways 19 the slots of which receive the diametrically opposite driving blocks 20 that are carried by the gear 10, these blocks 20 and the slots in the guideways 19 being upon the same 75 diametrical line whereby the disk 18 may shift with respect to the gear 10 along the diametrical line containing the blocks 19. The disk 18 is formed with a groove 21 disposed along the diametrical line that is at 80 right angles to the diametrical line containing the driving blocks 19 and guideways 20. The groove 21 receives a rib 22 carried by the disk 23 and disposed on the diametrical line of this disk. The disk 23 is fixed with 85 respect to the shaft 14 and the cylinder 13. By the means described for connecting the cylinder gear 10 with the printing cylinder 13 the peripheral speed of such cylinder will be maintained the same as the peripheral 90 speed of the cylinder gear 10 (which latter speed is measured at the pitch circle or driving line of the gear teeth) even though said cylinder and cylinder gear are laterally shifted relatively to one another causing 95 relative displacement of their axes. While the printing cylinder 13 is in printing position its axis is preferably co-incident with the axis of the cylinder gear 10 but when the cylinder 13 is tripped out of 100 printing position its axis is then non-coincident with the axis of its cylinder gear 10 but this cylinder gear maintains its own fixed axis so that the meshing thereof with the driving gear 9 and driven thereby is not 105 disturbed. The spur gear 9 meshes with spur gear 26 fixed upon shaft 25 journaled in the side frame 17. The sheet transfer cylinder 24 is fixed upon the shaft 25. The driven gear 9 thus drives the spur gear 26 to 110 rotate the sheet transfer cylinder 24 at the peripheral speed of the impression cylinder 8. In the press illustrated the cylinders 8 and 24 are each plural revolution cylinders and the cylinder 13 is a single revolution 115 cylinder, each of the cylinders 8 and 24 rotating two revolutions to each revolution of the cylinder 13.

The gear 10¹ meshes with intermediate gears 27 and 28 that are respectively in mesh 120 with driving pinions 29 of two inking couples and the driving pinion 30 of another inking couple. The pinions 29 and 30 drive metal distributing rollers 31 (upon the shafts of which their driving pinions are 125 fixed) which in turn drive the form rollers 32, these form rollers inking the printing surface of the printing element 13¹ of the printing cylinder 13. The ink is furnished from the ink supply roller 33 of the ink 130

fountain not shown by way of the usual feed roller 34 and distributing rollers 35.

Bearers 36 and 37 are formed on respective cylinders 8 and 13 by means of which a 5 rolling contact is afforded between said cylinders. Registering formations in the form of segmental racks 38 and 39 are affixed to the respective cylinders 8 and 13 and are adjustable and are disposed to engage one another at the initiation of the printing operation to insure exact registry of said cylinders at that point.

By way of general recapitulation of the gearing and its operation, it is stated that 15 the pinion 2 drives the train of gears 3, 6 and as gear 6 is fixed with respect to gear 10² this gear 6 drives the train of gears including gears 10², 10¹, which train of gears drives the two trains 27, 29 and 28, 30. As 20 the gears 10 and 10¹ are in fixed relation the gear 10¹ drives the train of gears that includes the gears 9 and 10 whereby not only is the cylinder 13 turned but the cylinder 8 is also turned. The gear 9 of the train of 25 gears 9, 10 is in mesh with the spur gear 26 whereby the sheet transfer cylinder 24 is turned.

The tripping mechanism employed may be of the general nature illustrated in my Patent No. 550,992, dated December 10, 1895, with necessary changes. The foot key 40 is normally held up by a spring 41 and is connected by a bell crank 42 with a connecting link 43 that is connected with a rocker arm 35 44 that in turn is fixed upon a rod 45 and on which rod there is fixed a cam arm 46 carrying a trip cam portion 47. Whenever the foot key is depressed the rod 45 of the tripping mechanism is turned to turn the cam arm 46 to move the upper end of the cam arm, where said cam portion 47 is disposed downwardly and with it cam 47 to allow the hook 48 to come into engagement with the tooth 49. The part 50 of hook 48, the rocking dog 51, which is pivoted on the rear side, of the arm 52 at 51¹ and the part 53 of tooth 49 constitute elements of a coupler that connects the printing cylinder 13 with its tripping cam 54. The tripping cam 54 is rotated by a gear 55 upon which the cam is fixedly located, the gear 55 in turn being rotated by the pinion 56 which is mounted for rotation upon the stud 57 fixed to the frame of the press. A gear 58 is fixedly mounted 55 upon a shaft 58¹ which is journaled in the frame of the press, and a pinion 57¹ is also fixedly mounted upon shaft 58¹ and meshes with the pinion 56. The shaft 1 passes through the machine from side to side and 60 has a pinion 59, meshing with the gear 58, fixedly mounted on the end thereof opposite that upon which the pinion 2 meshing with gear 3, as hereinbefore described, is carried. Thus the cam 54 is driven in timed relation 65 with the cylinders which are driven by shaft

1 through pinion 2 and gear 3. The cam groove 60 in cam 54 engages a cam roller 61 upon the arm 52 loose on shaft 62 that passes from side to side of the machine and to which shaft the tooth 49 and the stop finger 70 49¹ are fixed. The roller 61 is mounted upon the stud 63 upon the inner end of which the hook 48 is mounted to swing. The shaft 62 carries two eccentrics 64 upon each of which the sliding box member 65 rests, each sliding box member supporting a U-shaped extension 66 of a printing cylinder shaft box 15, there being thus one eccentric 64 in supporting relation to each printing cylinder box 15. Each shaft box 15 is formed in two sections that meet along the horizontal diameter of the shaft 14, these two sections being held in assembly with each other by bolts 66¹. A stationary spring supporting ledge 66² is carried by the press frame, there being one 80 such ledge upon each side of the press. This stationary ledge 66² passes between the sides of the vertically movable extensions 66 and supports the springs 66³. These springs support a large part of the weight of the 85 cylinder 13, there being sufficient weight unsupported by these springs to cause the cylinder to descend when the eccentrics 64 are turned to lower positions. The arc *a b* of the cam groove 60 is concentric with respect to the shaft 67 of the cam. The cam roller 61 is not bodily moved while engaging this part of the cam groove *a b* whereby the arm 52 is then at rest. The hook 48 carries a 90 cam roller 68 that may bear upon the operating tripping cam portion 47 of the arm 46. The arm 52 carries a stop pin 69 and hook 48 has a lug 70, the elements 69 and 70 preventing the hook 48 from separating any 95 farther from the tooth 49 than illustrated.

Each pair of eccentrics 64 upon the same shaft 62 has the position illustrated in Fig. 4 when the printing cylinder 13 is in its normal operating position, the centers of these eccentrics being normally positioned 100 slightly to the left of the vertical line passing through the centers of the shaft 62 and the shaft of the printing cylinder and being between this line and the stationary stop pin 71. As tooth 49 is in fixed relation to 105 the eccentrics 64 the stop pin 71 holds the shaft 62 from counter-clockwise rotation to hold the printing cylinder 13 in working position. The stop pin 71 illustrated is upon one side of the press (Fig. 3). There may 110 be a similar stop pin 71¹ on the other side of the press that is to be engaged by an arm 49¹ (Fig. 1) fixed upon the other end of the shaft 62 and positioned similarly to the tooth 49 to take part in preventing the turning of the shaft 62 and the eccentrics thereon. When the shaft 62 is turned clockwise the eccentrics 64, being fixed upon the shaft, are also turned clockwise so that the printing cylinder is lowered to non-printing posi- 115 120 125 130

tion (Fig. 3). This rotation of the shaft 62 and the eccentrics 64 cannot occur until after the part 50 of hook 48 is brought into position to enable it to be engaged by 5 the lower side of the tooth 49, following the depression of the foot key (at a time when the cylinder 13 is in a printing position) by the press attendant to lower the arm 46 and the cam part 47 thereon to permit the hook 10 48 to swing downwardly into the tooth engaging position. Operative engagement of the part 50 of the hook 48 with the tooth 49 can only occur while the arcal portion $a\ b$ of the cam groove 60 is passing by the cam 15 roller 61 which is when the line b^1 (shown on the cylinder 13, Fig. 3) has passed from the line a^1 to the position of the line b^1 . This tripping may be effected at a time when the cylinder 13 is in a printing position 20 and only during the time the leading edge of the printing form 13¹ travels through the arc $a^2\ b^2$ and during the time the eccentric cam portion a^3 of the cam groove 60 lying between the side b of the 25 arc $a\ b$ and the shaft 67 is passing by the roller 61 (Fig. 3). When the cam roller 61 is passing over the cam portion a^3 of the cam groove 60 between the side b of the arc $a\ b$ and the shaft 67, the part 50 of the 30 hook 48 (assuming that the attendant has pressed down the key 40 to drop the arm 46 to permit the hook 48 to engage the tooth 49) pulls the tooth 49 in a clockwise direction (while the leading end of the form 13¹ 35 is passing between the lines $a^2\ b^2$) to permit the printing cylinder 13 to be lowered by its own weight (Fig. 3). When the roller 61 is in the portion of the cam groove 60 between the shaft 67 and the side a of the arc 40 $a\ b$ (while the leading end of the form 13¹ is passing between the lines $a^4\ b^4$), the motion of the arm 52 is reversed, providing the foot key 40 had been previously released, whereupon the swinging extension 51 of the 45 arm 52 pushes upon the lug 53 carried by the tooth 49 to turn this tooth and the eccentrics 64 fixed with respect thereto counter clockwise back to the normal position. In coming back to this position the eccentrics 64 raise the printing cylinder to working 50 position. It is to be understood that the roller 68 (upon hook 48) supports the hook while this roller 68 rides over the tripping cam portion 47 when the arm 46 that carries 55 this cam 47 is in the normal raised position and while the printing cylinder is in its normal operating position. The cam arm 46 may be lowered at any time but should this arm be lowered while the roller 61 is not in 60 the arcal portion $a\ b$ of the cam slot 60 the swinging end of the hook will ride upon the crown of the tooth 49 until the roller 61 is received in the arcal portion $a\ b$ of said cam groove 60. 65 The cylinder 13 is maintained in its

tripped position, during any desired number of successive cycles of the machine or revolutions of the cylinder 13, without said cylinder necessarily returning to printing position during a portion of each cycle of the 70 machine or revolution of said cylinder, by the same foot key 40 that causes the cylinder 13 to be tripped. In order that the key 40 may serve this purpose it is in operating connection with a cam lever 40² that is 75 pivotally mounted upon the frame of the machine, the connection of the foot key with the cam lever 40² including a link 40³ pivotally connected at one end with the lever 40² and at its other end with an arm of the 80 bell crank 42. When the foot key 40 is depressed the lower end of the cam lever 40² is raised to be in the path of movement of and to engage the roller 40⁵ (Fig. 3) carried by the rocking dog 51, whereby this 85 rocking dog is raised and relieved of its function of coupling the actuated mechanism of cylinder 13 with such cylinder to prevent this mechanism from raising the cylinder 13 to printing position. In performing this function the dog 51 normally engages the part 53 of the tooth 49 and as the dog 51 is pivoted at 51¹ to the arm 52 the arm 52 is, through the intermediation of the dog, engaged with the part 53 of the tooth 90 49. This dog thus, in its normal position, serves as a coupler for connecting the tripping mechanism of cylinder 13 with the cylinder to enable such tripping mechanism to raise the cylinder 13 to printing position. 95 When the lower end of the lever 40² is thus raised it lifts the dog 51 out of the path of engagement of the portion 53 of the tooth 49, and permits the dog to ride over such tooth portion when the dog is swung by its operating cam 54. Thus the cylinder 13 is maintained in its lowered position as long as the foot key 40 is depressed and only when the foot key is depressed long enough for this purpose and if it is desired to repeatedly 100 trip the cylinder 13 the foot key may be maintained in a depressed position by turning the eccentric wheel 41¹ to engage the depressed key 40 whereby the cam 40² and parts connected therewith are maintained in the operating position shown by Fig. 3 to keep the dog 51 from engaging the tooth portion 53. 110 115 From the above description it will be noted that I have provided press actuated mechanism adapted to trip and restore, the mechanism being adapted to assume operative position both to function to trip and to restore, together with controlling mechanism for said mechanism adapted, when in one position, to allow said mechanism to function to trip and while in this position to render said mechanism functionless to restore, said controlling means, when in another position, being adapted to render the 120 125 130

press actuated mechanism functionless to trip and to allow the same to function to restore, the controlling relation of said controlling mechanism being such that it is not 5 operable in any of its positions to position either the tripping or restoring elements of said mechanism at a time when the opposite element is performing its function. This is due to the fact that cams 47 and 40² 10 can only engage their respective rollers 68 and 40⁵ of the respective movable elements 48 and 51 to position the same just previous to the period when each respective element would function to move the cylinder, the 15 time in which said controlling mechanism is in engaging relation with the restoring mechanism being later than the time when it is in engaging relation with the tripping mechanism, said elements being uncontrolled by 20 their respective cams during all other periods in the cycle of the machine and free to move under their gravitational influence and assume operative position except as limited by the engagement of said elements with 25 the crown of the tooth 49 to prevent said elements from moving to operative position as hereinbefore described.

Thus as the mechanism oscillates and trips the cylinder both of the elements 48 30 and 51 are engaged with the tooth 49 and prevent said tooth and its related mechanism from moving faster or slower than the cam 54 moves said elements 48 and 51 whereby any chattering of the mechanism or jar 35 as the cylinder reaches its fully tripped position is prevented. As the mechanism oscillates and operates to restore the cylinder to printing relation, both of said elements 48 and 51 are engaged with the tooth 49 in the same manner whereby an even movement of the cylinder and its related mechanism to printing position is also assured. The controlling mechanism is alternately engageable with the tripping and 40 restoring elements only at the opposite ends of the stroke of the oscillating movements of the same, and is only operable to control said mechanism relative to its tripping function when said mechanism is in its completely 45 restoring position and adapted to control said mechanism relative to its restoring function when said mechanism is in its completely restoring position and adapted to control said mechanism relative to its restoring 50 function when said mechanism is in its completely tripping position.

The sheets to be printed upon are fed to the impression cylinder 8 (Fig. 3) from the feed board or other feed structure 73 which 55 is mainly located in the quadrant containing the inking mechanism and projects into the quadrant containing the impression cylinder. The grippers 74 upon the impression cylinder 8 take the sheet, numbered 75, from the feed board carrying it through the line

76 joining the centers of the shafts 7 and 25 to the line 77 joining the centers of shafts 7 and 14, whereupon the first printing operation is initiated, the form 13¹ upon the printing cylinder 13 then having printing 70 relation with the sheet 75 upon the impression cylinder 8. A sheet 78 (Fig. 3) upon the sheet transfer cylinder 24 is shown preceding the sheet 75, sheet 78 being held by grippers 79 that hold the sheet during 75 a revolution of the sheet transfer cylinder 24 after the grippers 79 receive the sheet from grippers 74 preparatory to being transferred to the sheet delivery tapes 80. The first printing operation upon sheet 75 continues during the first revolution of the impression cylinder 8 and a part of the second revolution thereof (beginning with the time the impression cylinder 8 receives the sheet) 80 until the form 13¹ upon the printing cylinder 85 completes its printing upon the sheet 75. During the second revolution of the impression cylinder 8 the grippers 79 upon the sheet transfer cylinder 26 take the sheet 75 being printed upon by the form 13¹, the 90 grippers 74 releasing the sheet and the grippers 79 taking the sheet when these grippers of cylinders 8 and 26 are adjacent the line 76 during the second revolution of the impression cylinder 8. The transfer of sheet 95 75 from cylinder 8 to the sheet transfer cylinder 26 will not occur until these cylinders have each made nearly one revolution from the position shown in Fig. 3, and at the time grippers 74 again reach line 76. 100

The inking mechanism is substantially included in a quadrant of a circle having its center included in the normal axis of the printing cylinder and which quadrant is margined by the vertical diametrical line 105 81 of such circle and along which vertical diametrical line the printing cylinder is moved when tripped out of printing position and when restored to printing position. The inking mechanism is normally 110 unchanged in position so that when the printing cylinder is lowered to non-printing position the printing cylinder or form cylinder 13 is brought substantially out of inking relation with the inking mechanism. 115 The printing or form cylinder is lowered out of printing position while the leading or front end of the form 13¹ is traveling through the arc a² b². The printing or form cylinder 13 is raised into printing position 120 during the time the front end of the form passes through the arc a⁴ b⁴. It will be noted at this point that a relatively large blank or nonprinting portion 13² is provided 125 on the cylinder 13 and lies between the leading and trailing ends of the form 13¹, and that the engaging points of the impression cylinder 8 and the inking mechanism with the printing cylinder 13 lie within the circumferential extent of said blank portion 130

13². The tripping and restoring movements of the cylinder 13 are so timed relatively to the abovementioned engaging points that this blank portion is substantially passing 5 said engaging points while said cylinder is being tripped out of or restored into printing position. While the trailing end of the form 13¹ is passing by the lower end form rollers 32 of the inking mechanism 10 during the initial restoring movement, the restoring movement is not completed until after it has passed these rollers so that practically there is no inking of this portion of the form at such a time. Thus during 15 the restoring movement of the printing cylinder to printing position the trailing end of the form 13¹ passes the lower end form rollers 32 but substantially does not engage the same as the restoring movement 20 is not completed until said trailing portion has passed the same, whereby the form 13¹ receives no further ink from the inking mechanism in the revolution in which the form or printing cylinder was tripped. 25 If cylinder 13 should be tripped for more than one revolution, the form 13¹ will not receive any further ink in addition to that which it received the last time before the cylinder was tripped. The center of the 30 impression cylinder 8 and this cylinder itself are included in the next quadrant that is margined by the aforesaid diametrical line 81 and in the same half circle with the quadrant in which the inking mechanism 35 is disposed, this diametrical line dividing this half circle into such quadrants. The center of the sheet transfer cylinder 26 and this transfer cylinder itself are included in the same quadrant that contains the impression cylinder 8. The automatic mechanism 40 for restoring the printing cylinder 13 to printing position performs this function during the same revolution in which this cylinder is tripped, if the foot key 40 is 45 released at the proper time. This release of the foot key may occur immediately after the arc $a\ b$ has passed the roller 61 and after the roller 68 has passed out of engagement with the cam portion 47. The feed 50 board overlies the printing cylinder, its inking mechanism, and a part of the impression cylinder.

While I have herein shown and particularly described the preferred embodiment 55 of my invention I do not wish to be limited to the precise details of construction shown as changes may readily be made without departing from the spirit of my invention, but having thus described my invention I 60 claim as new and desire to secure by Letters Patent the following:

1. A rotary printing press including a printing couple one of whose members is a rotary form cylinder that may be tripped 65 into and out of printing relation with its

companion member; inking mechanism for the form cylinder and substantially out of inking relation with which the form cylinder is moved when tripped; tripping mechanism for said form cylinder; and automatic mechanism for restoring said form cylinder to printing position during the same revolution in which it is tripped. 70

2. A rotary printing press including a printing couple one of whose members is 75 a rotary form cylinder that is mounted for tripping movement along a diametrical line of the cylinder; inking mechanism substantially included in a quadrant of a circle having its center included in the normal axis 80 of the cylinder and margined by said diametrical line; tripping mechanism for tripping said cylinder substantially out of inking relation with said inking mechanism; and automatic mechanism for restoring said 85 form cylinder to printing position during the same revolution in which it is tripped.

3. A rotary printing press including a printing couple one of whose members is a rotary form cylinder that is mounted for 90 tripping movement along a diametrical line of the cylinder; inking mechanism substantially included in a quadrant of a circle having its center included in the normal axis 95 of the cylinder and margined by said diametrical line, said printing couple including an impression cylinder in the same half circle with the inking mechanism; tripping mechanism for tripping the form cylinder out of printing relation with the impression 100 cylinder and substantially out of inking relation with the inking mechanism; and automatic mechanism for restoring said form cylinder to printing position during the same revolution in which it is tripped. 105

4. A rotary printing press including a printing couple one of whose members is a rotary form cylinder that is mounted for tripping movement along a diametrical line of the cylinder; inking mechanism substantially included in a quadrant of a circle having its center included in the normal axis of the cylinder and margined by said diametrical line, said printing couple including an impression cylinder in the other quadrant of the same half circle with the inking mechanism; tripping mechanism for tripping the form cylinder out of printing relation with the impression cylinder and substantially out of inking relation with the 110 inking mechanism; and automatic mechanism for restoring said form cylinder to printing position during the same revolution in which it is tripped. 115

5. A rotary printing press including a 125 printing couple one of whose members is a rotary form cylinder that is mounted for tripping movement along a diametrical line of the cylinder; inking mechanism substantially included in a quadrant of a circle 130

having its center included in the normal axis of the cylinder and margined by said diametrical line, said printing couple including an impression cylinder in the other quadrant of the same half circle with the inking mechanism; tripping mechanism for tripping the form cylinder out of printing relation with the impression cylinder and substantially out of inking relation with the inking mechanism, the diametrical line along which the form cylinder moves dividing said half circuit into said quadrants; and automatic mechanism for restoring said form cylinder to printing position during the same revolution in which it is tripped.

6. A rotary printing press including a printing couple one of whose members is a single revolution rotary form cylinder that may be tripped into and out of printing relation with its companion member that is in the form of a plural revolution impression cylinder; inking mechanism for the form cylinder and substantially out of inking relation with which the form cylinder is moved when tripped; tripping mechanism for said form cylinder; and automatic mechanism for restoring said form cylinder to printing position during the same revolution in which it is tripped.

30 7. A rotary printing press including a printing couple one of whose members is a single revolution rotary form cylinder that is mounted for tripping movement along a diametrical line of the cylinder and the other of whose members is a plural revolution impression cylinder; inking mechanism substantially included in a quadrant of a circle having its center included in the normal axis of the cylinder and margined by said diametrical line; tripping mechanism for tripping said cylinder substantially out of inking relation with said inking mechanism; and automatic mechanism for restoring said form cylinder to printing position during the same revolution in which it is tripped.

8. A rotary printing press including a printing couple one of whose members is a single revolution rotary form cylinder that is mounted for tripping movement along a diametrical line of the cylinder; inking mechanism substantially included in a quadrant of a circle having its center included in the normal axis of the cylinder and margined by said diametrical line, said printing couple including a plural revolution impression cylinder in the same half circle with the inking mechanism; tripping mechanism for tripping the form cylinder out of printing relation with the impression cylinder and substantially out of inking relation with the inking mechanism; and automatic mechanism for restoring said form cylinder to printing position during the same revolution in which it is tripped.

9. A rotary printing press including a printing couple one of whose members is a single revolution rotary form cylinder that is mounted for tripping movement along a diametrical line of the cylinder; inking mechanism substantially included in a quadrant of a circle having its center included in the normal axis of the cylinder and margined by said diametrical line, said printing couple including a plural revolution impression cylinder in the other quadrant of the same half circle with the inking mechanism; tripping mechanism for tripping the form cylinder out of printing relation with the impression cylinder and substantially out of inking relation with the inking mechanism; and automatic mechanism for restoring said form cylinder to printing position during the same revolution in which it is tripped.

10. A rotary printing press including a printing couple one of whose members is a single revolution rotary form cylinder that is mounted for tripping movement along a diametrical line of the cylinder; inking mechanism substantially included in a quadrant of a circle having its center included in the normal axis of the cylinder and margined by said diametrical line, said printing couple including a plural revolution impression cylinder in the other quadrant of the same half circle with the inking mechanism; tripping mechanism for tripping the form cylinder out of printing relation with the impression cylinder and substantially out of inking relation with the inking mechanism, the diametrical line along which the form cylinder moves dividing said half circle into said quadrants; and automatic mechanism for restoring said form cylinder to printing position during the same revolution in which it is tripped.

11. A rotary printing press including a printing couple one of whose members is a rotary form cylinder that is mounted for tripping movement along a diametrical line of the cylinder; inking mechanism substantially included in a quadrant of a circle having its center included in the normal axis of the cylinder and margined by said diametrical line, said printing couple including an impression cylinder in the same half circle with the inking mechanism, the form cylinder rotating from the inking mechanism toward the impression cylinder; tripping mechanism for tripping the form cylinder out of printing relation with the impression cylinder and substantially out of inking relation with the inking mechanism; and automatic mechanism for restoring said form cylinder to printing position during the same revolution in which it is tripped.

12. A rotary printing press including a printing couple one of whose members is a rotary form cylinder that is mounted for

tripping movement along a diametrical line of the cylinder; inking mechanism substantially included in a quadrant of a circle having its center included in the normal axis of the cylinder and margined by said diametrical line, said printing couple including an impression cylinder in the other quadrant of the same half circle with the inking mechanism, the form cylinder rotating from the inking mechanism toward the impression cylinder; tripping mechanism for tripping the form cylinder out of printing relation with the impression cylinder and substantially out of inking relation with the inking mechanism; and automatic mechanism for restoring said form cylinder to printing position during the same revolution in which it is tripped.

13. A rotary printing press including a printing couple one of whose members is a rotary form cylinder that is mounted for tripping movement along a diametrical line of the cylinder; inking mechanism substantially included in a quadrant of a circle having its center included in the normal axis of the cylinder and margined by said diametrical line, said printing couple including an impression cylinder in the other quadrant of the same half circle with the inking mechanism, the form cylinder rotating from the inking mechanism toward the impression cylinder; tripping mechanism for tripping the form cylinder out of printing relation with the impression cylinder and substantially out of inking relation with the inking mechanism, the diametrical line along which the form cylinder moves dividing said half circuit into said quadrants; and automatic mechanism for restoring said form cylinder to printing position during the same revolution in which it is tripped.

14. A rotary printing press including a printing couple one of whose members is a single revolution rotary form cylinder that is mounted for tripping movement along a diametrical line of the cylinder; inking mechanism substantially included in a quadrant of a circle having its center included in the normal axis of the cylinder and margined by said diametrical line, said printing couple including a plural revolution impression cylinder in the same half circle with the inking mechanism, the form cylinder rotating from the inking mechanism toward the impression cylinder; tripping mechanism for tripping the form cylinder out of printing relation with the impression cylinder and substantially out of inking relation with the inking mechanism; and automatic mechanism for restoring said form cylinder to printing position during the same revolution in which it is tripped.

15. A rotary printing press including a printing couple one of whose members is a single revolution rotary form cylinder that

is mounted for tripping movement along a diametrical line of the cylinder; inking mechanism substantially included in a quadrant of a circle having its center included in the normal axis of the cylinder and margined by said diametrical line, said printing couple including a plural revolution impression cylinder in the other quadrant of the same half circle with the inking mechanism, the form cylinder rotating from the inking mechanism toward the impression cylinder; tripping mechanism for tripping the form cylinder out of printing relation with the impression cylinder and substantially out of inking relation with the inking mechanism; and automatic mechanism for restoring said form cylinder to printing position during the same revolution in which it is tripped.

16. A rotary printing press including a printing couple one of whose members is a single revolution rotary form cylinder that is mounted for tripping movement along a diametrical line of the cylinder; inking mechanism substantially included in a quadrant of a circle having its center included in the normal axis of the cylinder and margined by said diametrical line, said printing couple including a plural revolution impression cylinder in the other quadrant of the same half circle with the inking mechanism, the form cylinder rotating from the inking mechanism toward the impression cylinder; tripping mechanism for tripping the form cylinder out of printing relation with the impression cylinder and substantially out of inking relation with the inking mechanism, the diametrical line along which the form cylinder moves dividing said half circle into said quadrants; and automatic mechanism for restoring said form cylinder to printing position during the same revolution in which it is tripped.

17. A rotary printing press including a printing couple one of whose members is a rotary form cylinder that may be tripped into and out of printing relation with its companion member, this companion member being in the form of an impression cylinder; inking mechanism for the form cylinder and substantially out of inking relation with which the form cylinder is moved when tripped; tripping mechanism for said form cylinder, the line of tripping movement of the form cylinder being angular to the line joining the centers of the form cylinder and impression cylinder; and automatic mechanism for restoring said form cylinder to printing position during the same revolution in which it is tripped.

18. A rotary printing press including a printing couple one of whose members is a single revolution rotary form cylinder that may be tripped into and out of printing relation with its companion member that is in

the form of a plural revolution impression cylinder; inking mechanism for the form cylinder and substantially out of inking relation with which the form cylinder is moved when tripped; tripping mechanism for said form cylinder, the line of movement of the form cylinder being angular to the line joining the centers of the form cylinder and impression cylinder; and automatic mechanism for restoring said form cylinder to printing position during the same revolution in which it is tripped.

19. A rotary printing press including a printing couple one of whose members is a rotary form cylinder that may be tripped into and out of printing relation with its companion member, this companion member being in the form of an impression cylinder; inking mechanism for the form cylinder and substantially out of inking relation with which the form cylinder is moved when tripped, the form cylinder rotating from the inking mechanism toward the impression cylinder; tripping mechanism for said form cylinder, the line of tripping movement of the form cylinder being angular to the line joining the centers of the form cylinder and impression cylinder; and automatic mechanism for restoring said form cylinder to printing position during the same revolution in which it is tripped.

20. A rotary printing press including a printing couple one of whose members is a single revolution rotary form cylinder that may be tripped into and out of printing relation with its companion member that is in the form of a plural revolution impression cylinder; inking mechanism for the form cylinder and substantially out of inking relation with which the form cylinder is moved when tripped, the form cylinder rotating from the inking mechanism toward the impression cylinder; tripping mechanism for said form cylinder, the line of movement of the form cylinder being angular to the line joining the centers of the form cylinder and impression cylinder; and automatic mechanism for restoring said form cylinder to printing position during the same revolution in which it is tripped.

21. In a printing press, the combination with a movably mounted cylinder, of press actuated mechanism in operative relation therewith adapted to trip and restore the same, and controlling mechanism for said press actuated mechanism and adapted to be positioned to allow said press actuated mechanism to function to trip and while in this position to be engaged by said press actuated mechanism to render the same inoperative to restore at a later period in the cycle of operation than that in which said press actuated mechanism was allowed to function to trip.

22. In a printing press, the combination

with a movably mounted cylinder, of press actuated mechanism in operative relation therewith adapted to trip and restore the same, and controlling mechanism for said press actuated mechanism and adapted to be positioned to allow said press actuated mechanism to function to trip and while in this position to be engaged by said press actuated mechanism to render the same inoperative to restore at a later period in the cycle of operation than that in which said press actuated mechanism was allowed to function to trip, said controlling mechanism being adapted to be only engaged by said press actuated mechanism to render the same functionless to trip when in one position and to be only engaged by said press actuated mechanism to render the same functionless to restore when in another position.

23. In a printing press, the combination with a movably mounted cylinder, of press actuated mechanism in operative relation therewith and adapted to assume an operative position to trip and restore said cylinder, and controlling mechanism for said press actuated mechanism and adapted to be positioned to allow said press actuated mechanism to function to trip and while in this position to be engaged by said press actuated mechanism to render the same inoperative to restore at a later period in the cycle of operation than that in which said press actuated mechanism was allowed to function to trip.

24. In a printing press, the combination with a movably mounted cylinder, of press actuated mechanism in operative relation therewith and adapted to assume an operative position to trip and restore said cylinder, and controlling mechanism for said press actuated mechanism and adapted to be positioned to allow said press actuated mechanism to function to trip and while in this position to be engaged by said press actuated mechanism to render the same inoperative to restore at a later period in the cycle of operation than that in which said press actuated mechanism was allowed to function to trip, said controlling mechanism being adapted to be engaged only by said press actuated mechanism to render the same functionless to trip when in one position and to be engaged only by said press actuated mechanism to render the same functionless to restore when in another position.

25. In a printing press the combination with a movably mounted cylinder, of press actuated mechanism in operative connection therewith and adapted to trip and restore said cylinder, an element included in said mechanism adapted to be moved to render said mechanism functionless to trip, a second element included in said mechanism adapted to be moved to render said mechanism functionless to restore, and a control

ling mechanism adapted to be engaged by each of said elements to establish controlling relation therewith at different periods in the cycle of operations.

- 5 26. In a printing press the combination with a movably mounted cylinder, of press actuated mechanism in operative connection therewith, and adapted to trip and restore said cylinder, an element included in
- 10 said mechanism adapted to be moved to render said mechanism functionless to trip, a second element included in said mechanism and adapted to be moved to render said mechanism functionless to restore, and a controlling mechanism adapted to be engaged by each of said elements to establish controlling relation therewith at different periods in the cycle of operations, said controlling means being adapted to be engaged
- 15 only by one of said elements to move that element into inoperative position when in one position and to be engaged only by the other element to move that element into inoperative position when in another position.
- 20 27. In a printing press the combination with a movably mounted cylinder, of a press actuated mechanism having operative relation with said cylinder for tripping and restoring the same, a movable element included in said mechanism adapted to be moved to render said mechanism inoper-
- 25 ative to trip, a second movable element included in said mechanism adapted to be moved to render said mechanism inoper-
- 30 ative to restore, and controlling mechanism for said movable elements adapted to assume a controlling relation with said controlling mechanism at different periods in the cycle of operation, each element being out of con-
- 35 trol of said controlling mechanism when the other element is in controlling relation therewith.
- 40 28. In a printing press the combination with a movably mounted cylinder, of a press actuated mechanism having operative relation with said cylinder for tripping and restoring the same, a movable element included in said mechanism adapted to be moved to render said mechanism inoper-
- 45 ative to trip, a second movable element included in said mechanism adapted to be moved to render said mechanism inoperative to restore, and controlling mechanism for said movable elements adapted to assume a con-
- 50 troling relation with said controlling mechanism at different periods in the cycle of operation, each element being out of the control of said controlling mechanism when the other element is in controlling relation therewith,
- 55 29. In a printing press the combination with a movably mounted cylinder, of a press actuated mechanism having operative relation with said cylinder for tripping and restoring the same, a movable element included in said mechanism adapted to be moved to render said mechanism inoper-
- 60 ative to trip, said controlling mechanism being adapted to be engaged only by one of said elements to move that element into inoperative position when in one position and to be engaged only by the other element to

move that element into inoperative position when in another position. 65

29. In a printing press the combination with a movably mounted cylinder, of a press actuated mechanism having operative relation with said cylinder for tripping and restoring the same, a movable element included in said mechanism and adapted to be moved to render said mechanism inoperative and adapted to assume an operative position, a second movable element included in said mechanism adapted to be moved to render said mechanism inoperative to restore and adapted to assume an operative position, and controlling mechanism for said movable elements 80 adapted to assume controlling relation with said controlling mechanism at different periods in the cycle of operation, each element being out of the control of said controlling mechanism when the other element 85 is in controlling relation therewith.

30. In a printing press the combination with a movably mounted cylinder, of a press actuated mechanism having operative relation with said cylinder for tripping and 90 restoring the same, a movable element included in said mechanism and adapted to be moved to render said mechanism inoperative and adapted to assume an operative position, a second movable element included in 95 said mechanism adapted to be moved to render said mechanism inoperative to restore and adapted to assume an operative position, and controlling mechanism for said movable elements adapted to assume a 100 controlling relation with said controlling mechanism at different periods in the cycle of operation, each element being out of the control of said controlling mechanism when the other element is in controlling relation 105 therewith, said controlling mechanism being adapted to be engaged only by one of said elements to move that element into inoperative position when in one position and to be engaged only by the other element to 110 move that element into operative position when in another position.

31. In a printing press the combination with a movably mounted cylinder, of a press actuated oscillating mechanism having 115 operative relation with said cylinder for tripping and restoring the same, a movable element included in said mechanism adapted to be moved to render said oscillating mechanism inoperative to trip and adapted to 120 assume operative position, a second movable element included in said mechanism adapted to be moved to render said oscillating mechanism inoperative to restore and adapted to assume an operative position, and controlling mechanism for said movable elements so disposed that one movable element 125 is in controlling relation therewith at

each end of the stroke of said oscillating mechanism.

32. In a printing press the combination with a movably mounted cylinder, of a press actuated oscillating mechanism having operative relation with said cylinder for tripping and restoring the same, a movable element included in said mechanism adapted to be moved to render said oscillating mechanism inoperative to trip and adapted to assume operative position, a second movable element included in said mechanism adapted to be moved to render said oscillating mechanism inoperative to restore and adapted to 5 assume an operative position, and controlling mechanism for said movable elements so disposed that one movable element is in controlling relation therewith at each end of the stroke of said oscillating mechanism, 10 said controlling mechanism being adapted when in one position to be engaged only by one element to move that element into inoperative position and when in another position to be engaged only by the other element to move that element into inoperative 15 position.

33. In a printing press the combination with a movably mounted cylinder, press actuated mechanism in operative relation with 20 said cylinder for tripping and restoring the same, a movable element included in said mechanism and adapted to be moved to render said mechanism inoperative to trip and adapted to assume operative position, 25 a second movable element included in said mechanism adapted to be moved to render said mechanism inoperative to restore, and controlling mechanism for said movable elements and adapted to be engaged by said 30 first mentioned element to move that element into inoperative position only at the time when said press actuated mechanism is in its completely restoring position and adapted to be engaged by said second element to move that element into inoperative 35 position only at the time when said press actuated mechanism is in its completely tripping position.

34. In a printing press the combination with a movably mounted cylinder, press actuated mechanism in operative relation with 40 said cylinder for tripping and restoring the same, a movable element included in said mechanism and adapted to be moved to render said mechanism inoperative to trip and adapted to assume operative position, a second movable element included in said mechanism adapted to be moved to render said mechanism inoperative to restore, and 45 controlling mechanism for said movable elements and adapted to be engaged by said first mentioned element to move that element into inoperative position only at the time when said press actuated mechanism is

in its completely restoring position and 50 adapted to be engaged by said second element to move that element into inoperative position only at the time when said press actuated mechanism is in its completely tripping position, said controlling mechanism being adapted when in one position to be engaged only by one element to move that element into inoperative position and when in another position to be engaged only by the other element to move that element 55 into inoperative position.

35. In a printing press the combination with a movably mounted single revolution cylinder, of press actuated mechanism in operative connection therewith and adapted 60 to trip and restore said cylinder in the same revolution in which it is tripped, an element included in said mechanism adapted to be moved to render said mechanism functionless to trip, a second element included in 65 said mechanism adapted to be moved to render said mechanism functionless to restore, and a controlling mechanism adapted to be engaged by each of said elements to establish controlling relation therewith at 70 different periods in the cycle of operations.

36. In a printing press, the combination with a movably mounted single revolution cylinder, of press actuated mechanism in operative relation therewith adapted to trip 75 and restore said cylinder in the same revolution in which it is tripped, and controlling mechanism for said press actuated mechanism and adapted to be positioned to allow said press actuated mechanism to function to 80 trip and while in this position to be engaged by said press actuated mechanism to render the same inoperative to restore at a later period in the cycle of operation than that in which said press actuated mechanism was 85 allowed to function to trip.

37. In a printing press the combination with a movably mounted single revolution cylinder, of press actuated mechanism in operative relation therewith adapted to trip 90 and restore the said cylinder in the same revolution in which it is tripped, and controlling mechanism for said press actuated mechanism and adapted to be positioned to allow said press actuated mechanism to function to trip and while in this position to be engaged by said press actuated mechanism to render the same inoperative to restore at a later period in the cycle of operations than that in which said press actuated mechanism was allowed to function to trip, said controlling mechanism being adapted to be engaged only by said press actuated mechanism to render the same 95 functionless to trip when in one position and to be engaged only by said press actuated mechanism to render the same functionless to restore when in another position,

38. In a printing press the combination with a movably mounted single revolution cylinder, of press actuated mechanism in operative relation therewith and adapted to assume an operative position to trip and restore said cylinder in the same revolution in which it is tripped, and controlling mechanism for said press actuated mechanism and adapted to be positioned to allow said press actuated mechanism to function to trip and while in this position to be engaged by said press actuated mechanism to render the same inoperative to restore at a later period in the cycle of operations than that in which said press actuated mechanism was allowed to function to trip.
39. In a printing press the combination with a movably mounted single revolution cylinder, of press actuated mechanism in operative relation therewith and adapted to assume an operative position to trip and restore said cylinder, in the same revolution in which it is tripped, and controlling mechanism for said press actuated mechanism and adapted to be positioned to allow said press actuated mechanism to function to trip and while in this position to be engaged by said press actuated mechanism to render the same inoperative to restore at a later period in the cycle of operations than that in which said press actuated mechanism was allowed to function to trip, said controlling mechanism being adapted to be engaged only by said press actuated mechanism to render the same functionless to trip when in one position and to be engaged only by said press actuated mechanism to render the same functionless to restore when in another position.
40. In a printing press the combination with a movably mounted single revolution cylinder, of a press actuated mechanism having operative relation with said cylinder for tripping and restoring the same in one revolution of said cylinder, a movable element included in said mechanism adapted to be moved to render said mechanism inoperative to trip, a second movable element included in said mechanism adapted to be moved to render said mechanism inoperative to restore, and controlling mechanism for said movable elements adapted to assume a controlling relation with said controlling mechanism at different periods in the cycle of operation, each element being out of the control of said controlling mechanism when the other element is in controlling relation therewith.
41. In a printing press the combination with a movably mounted single revolution cylinder, of a press actuated mechanism having operative relation with said cylinder for tripping and restoring the same in one revolution of said cylinder, a movable ele-

ment included in said mechanism and adapted to be moved to render said mechanism inoperative and adapted to assume an operative position, a second movable element included in said mechanism adapted to be moved to render said mechanism inoperative to restore and adapted to assume an operative position, and controlling mechanism for said movable elements adapted to assume a controlling relation with said controlling mechanism at different periods in the cycle of operation, each element being out of the control of said controlling mechanism when the other element is in controlling relation therewith.

42. In a printing press the combination with a movably mounted single revolution cylinder, of a press actuated oscillating mechanism having operative relation with said cylinder for tripping and restoring the same in one revolution of said cylinder, a movable element included in said mechanism adapted to be moved to render said oscillating mechanism inoperative to trip and adapted to assume operative position, a second movable element included in said mechanism adapted to be moved to render said oscillating mechanism inoperative to restore and adapted to assume an operative position, and controlling mechanism for said movable elements so disposed that one movable element is in controlling relation therewith at each end of the stroke of said oscillating mechanism.

43. In a printing press the combination with a movably mounted single revolution cylinder, press actuated mechanism in operative relation with said cylinder for tripping and restoring the same in one revolution of said cylinder, a movable element included in said mechanism and adapted to be moved to render said mechanism inoperative to trip and adapted to assume operative position, a second movable element included in said mechanism adapted to be moved to render said mechanism inoperative to restore, and controlling mechanism for said movable elements and adapted to be engaged by said first mentioned element to move that element into inoperative position only at the time when said press actuated mechanism is in its completely restoring position to be engaged by said second element to move that element into inoperative position only at the time when said press actuated mechanism is in its completely tripping position.

44. In a printing press the combination with an impression cylinder, of a complementary single revolution printing cylinder that may be tripped out of and restored back into printing relation with said impression cylinder, inking mechanism for said printing cylinder and substantially out of inking

relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, and press actuated mechanism in operative connection with said printing cylinder for tripping and restoring the same in the same revolution in which it is tripped and so timed relatively to said blank portion that said printing cylinder is tripped substantially out of printing position and restored back into printing position during the periods when said blank portion is passing said engagement points.

45. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion and press actuated mechanism in operative connection with said printing cylinder for tripping and restoring the same and so timed relatively to said blank portion that said printing cylinder is tripped substantially out of printing position and restored back into printing position during the periods when said blank portion is passing said engagement points.

46. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder for tripping and restoring the same and so timed relatively to said blank portion that said printing cylinder is tripped substantially out of printing position and restored back into printing position during the periods when said blank portion is passing said engagement points,

and controlling mechanism for said press actuated mechanism and adapted to be positioned to allow said press actuated mechanism to function to trip and while in this position to be engaged by said press actuated mechanism to render the same inoperative to restore at a later period in the cycle of operation than that in which said press actuated mechanism was allowed to function to trip.

47. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder for tripping and restoring the same and so timed relatively to said blank portion that said printing cylinder is tripped substantially out of printing position and restored back into printing position during the periods when said blank portion is passing said engagement points, and controlling mechanism for said press actuated mechanism and adapted to be positioned to allow said press actuated mechanism to function to trip and while in this position to be engaged by said press actuated mechanism to render the same inoperative to restore at a later period in the cycle of operation than that in which said press actuated mechanism was allowed to function to trip, said controlling mechanism being adapted to be engaged only by said press actuated mechanism to render the same functionless to trip when in one position and to be engaged only by said press actuated mechanism to render the same functionless to restore when in another position.

48. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder for tripping and restoring the same and so timed relatively to said blank portion that said printing cylinder is tripped substantially out of printing position and restored back into printing position during the periods when said blank portion is passing said engagement points,

nection with said printing cylinder adapted to assume an operative position for tripping and restoring the same and so timed relatively to said blank portion that said printing cylinder is tripped substantially out of printing position and restored back into printing position during the periods when said blank portion is passing said engagement points, and controlling mechanism for 5 said press actuated mechanism and adapted to be positioned to allow said press actuated mechanism to function to trip and while in this position to be engaged by said press actuated mechanism to render the same inoperative 10 to restore at a later period in the cycle of operations than that in which said press actuated mechanism was allowed to function to trip.

49. In a printing press the combination 20 with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder, and adapted to trip and restore said cylinder, an element included in said mechanism adapted to be moved to render said mechanism functionless to trip, a second element included in said mechanism adapted to be moved to render said mechanism functionless to restore, and a controlling mechanism adapted to be engaged by each of said elements to establish controlling relation therewith at different periods in the cycle of operations.

50. In a printing press the combination 25 with an impression cylinder, of a complementary printing cylinder that may be tripped out of and restored back into printing relation with said impression cylinder, inking mechanism for said printing cylinder, and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder adapted to assume an operative position for tripping and restoring the same and so timed relatively to said blank portion that said printing cylinder is tripped substantially out of printing position and restored back into printing position during the periods when said blank portion is passing said engagement points, and controlling mechanism for 30 said press actuated mechanism and adapted to be positioned to allow said press actuated mechanism to function to trip and while in this position to be engaged by said press actuated mechanism to render the same inoperative to restore at a later period in the cycle of operations than that in which said press actuated mechanism was allowed to function to trip, said controlling mechanism being adapted to be engaged only by said press actuated mechanism to render the same functionless to trip when in one position and 35 to be engaged only by said press actuated mechanism to render the same functionless to restore when in another position.

51. In a printing press the combination 40 with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder, and adapted to trip and restore said cylinder, an element included in said mechanism adapted to be moved to render said mechanism functionless to trip, a second element included in said mechanism adapted to be moved to render said mechanism functionless to restore, and a controlling mechanism adapted to be engaged by each of said elements to establish controlling relation therewith at different periods in the cycle of operations, said controlling means being adapted to be engaged only by one of said elements to move that element into inoperative position when in one position and to be engaged only by the other element to move that element into inoperative position when in another position.

52. In a printing press the combination 45 with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of

printing cylinder when it is in the position 65 into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder, and adapted to trip and restore said cylinder, an element included in said mechanism adapted to be moved to render said mechanism functionless to trip, a second element included in said mechanism adapted to be moved to render said mechanism functionless to restore, and a controlling mechanism adapted to be engaged by each of said elements to establish controlling relation therewith at different periods in the cycle of operations.

53. In a printing press the combination 70 with an impression cylinder, of a complementary printing cylinder that may be tripped out of and restored back into printing relation with said impression cylinder, inking mechanism for said printing cylinder, and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, press actuated mechanism in operative connection with said printing cylinder, and adapted to trip and restore said cylinder, an element included in said mechanism adapted to be moved to render said mechanism functionless to trip, a second element included in said mechanism adapted to be moved to render said mechanism functionless to restore, and a controlling mechanism adapted to be engaged by each of said elements to establish controlling relation therewith at different periods in the cycle of operations, said controlling means being adapted to be engaged only by one of said elements to move that element into inoperative position when in one position and to be engaged only by the other element to move that element into inoperative position when in another position.

54. In a printing press the combination 75 with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of

5 said impression cylinder and said inking mechanism with said printing cylinder lying within the circumferential extent of said blank portion, press actuated mechanism in operative connection with said printing cylinder for tripping and restoring the same, a movable element included in said mechanism adapted to be moved to render said mechanism inoperative to trip, a second movable element included in said mechanism adapted to be moved to render said mechanism inoperative to restore, and controlling mechanism for said movable elements adapted to assume a controlling relation with said controlling mechanisms at different periods in the cycle of operation, each element being out of the control of said controlling mechanism when the other element is in controlling relation therewith.

10 53. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or

15 nonprinting portion, the engagement points of said impression cylinder and said inking mechanism with said printing cylinder lying within the circumferential extent of said blank portion, press actuated mechanism in operative connection with said printing cylinder for tripping and restoring the same, a movable element included in said mechanism adapted to be moved to render said mechanism inoperative to trip, a second

20 movable element included in said mechanism adapted to be moved to render said mechanism inoperative to restore, and controlling mechanism for said movable elements adapted to assume a controlling relation with said

25 controlling mechanisms at different periods in the cycle of operation, each element being out of the control of said controlling mechanism when the other element is in controlling relation therewith, said controlling

30 mechanism being adapted to be engaged only by one of said elements to move that element into inoperative position when in one position and to be engaged only by the other element to move that element into in-

35 operative position when in another position.

54. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped,

said printing cylinder having a blank 65 or nonprinting portion, the engagement points of said impression cylinder and said inking mechanism with said printing cylinder lying within the circumferential extent of said blank portion, press actuated mechanism in operative connection with said printing cylinder for tripping and restoring the same, a movable element included in said mechanism and adapted to be moved to render said mechanism inoperative and 70 adapted to assume an operative position, a second movable element included in said mechanism adapted to be moved to render said mechanism inoperative to restore and adapted to assume an operative position, 75 and controlling mechanism for said movable elements adapted to assume a controlling relation with said controlling mechanism at different periods in the cycle of operation, each element being out of the control of said 80 controlling mechanism when the other element is in controlling relation therewith. 85

55. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, 90 said printing cylinder having a blank or nonprinting portion, the engagement points of said impression cylinder and said inking mechanism with said printing cylinder lying 95 within the circumferential extent of said blank portion, press actuated mechanism in operative connection with said printing cylinder for tripping and restoring the same, a movable element included in said mechanism 100 and adapted to be moved to render said mechanism inoperative and adapted to assume an operative position, a second movable element included in said mechanism adapted to be moved to render said mechanism inoperative 105 to restore and adapted to assume an operative position, and controlling mechanism for said movable elements adapted to assume a controlling relation with said controlling mechanism at different periods in 110 the cycle of operation, each element being out of the control of said controlling mechanism when the other element is in controlling relation therewith, said controlling mechanism being adapted to be engaged only 115 by one of said elements to move that element into inoperative position when in one position and to be engaged only by the other element to move that element into inoperative position when in another position. 120

56. In a printing press the combination with an impression cylinder, of a complementary printing cylinder that may be tripped

out of and restored back into printing relation with said impression cylinder, inking mechanism for said printing cylinder and substantially out of inking relation with 5 the printing cylinder when it is in the position into which it is moved when tripped, said printing cylinder having a blank or nonprinting portion, the engagement points of said impression cylinder and said inking 10 mechanism with said printing cylinder lying within the circumferential extent of said blank portion, of a press actuated oscillating mechanism having operative relation with said cylinder for tripping and restoring the same, a movable element included 15 in said mechanism adapted to be moved to render said oscillating mechanism inoperative to trip and adapted to assume operative position, a second movable element included in said mechanism adapted to be moved to render said oscillating mechanism inoperative to restore and adapted to assume an operative position, and controlling mechanism for said movable elements 20 so disposed that one movable element is in controlling relation therewith at each end of the stroke of said oscillating mechanism.

57. In a printing press the combination with an impression cylinder, of a complementary printing cylinder that may be tripped out of and restored back into printing relation with said impression cylinder, inking mechanism for said printing cylinder and substantially out of inking relation 25 with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, of a press actuated oscillating mechanism having operative relation with said cylinder for tripping and restoring the same, a movable element included 30 in said mechanism adapted to be moved to render said oscillating mechanism inoperative to trip and adapted to assume operative position, a second movable element included in said mechanism adapted to be moved to render said oscillating mechanism inoperative to restore and adapted to assume an operative position, and controlling mechanism for said movable elements 35 so disposed that one movable element is in controlling relation therewith at each end of the stroke of said oscillating mechanism.

58. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, of a press actuated mechanism in operative connection with said printing cylinder for tripping and restoring the same, a movable element included in said mechanism and adapted to be moved to render said mechanism inoperative to trip and adapted to assume operative position, a second movable element included in said mechanism adapted to be moved to render said mechanism inoperative to restore, and controlling mechanism for said movable elements and adapted to be engaged by said first mentioned element to move that element into inoperative position only at the time when said press actuated mechanism is in its completely restoring position and adapted to be engaged by said second element to move that element into inoperative position only at the time when said press actuated mechanism is in its completely tripping position.

59. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, of a press actuated mechanism in operative connection with said printing cylinder for tripping and restoring the same, a movable element included in said mechanism and adapted to be moved to render said mechanism inoperative to trip and adapted to assume operative position, a second movable element included in said mechanism adapted to be moved to render said mechanism inoperative to restore, and controlling mechanism for said movable elements and adapted to be engaged by said first mentioned element to move that element into inoperative position only at the time when said press actuated mechanism is in its completely tripping position.

60. In a printing press the combination with an impression cylinder, of a complementary printing cylinder that may be tripped out of and restored back into printing relation with said impression cylinder, inking mechanism for said printing cylinder and substantially out of inking relation with the printing cylinder when it is in the position into which it is moved when tripped, said printing cylinder having a blank or nonprinting portion, the engagement points of said impression cylinder and said inking mechanism with said printing cylinder lying within the circumferential extent of said blank portion, of a press actuated mechanism in operative connection with said printing cylinder for tripping and restoring the same, a movable element included in said mechanism and adapted to be moved to render said mechanism inoperative to trip and adapted to assume operative position, a second movable element included in said mechanism adapted to be moved to render said mechanism inoperative to restore, and controlling mechanism for said movable elements and adapted to be engaged by said first mentioned element to move that element into inoperative position only at the time when said press actuated mechanism is in its completely tripping position.

completely restoring position and adapted to be engaged by said second element to move that element into operative position only at the time when said press actuated mechanism is in its completely tripping position, said controlling mechanism being adapted when in one position to be engaged only by one element to move that element into in-

operative position and when in another position to be engaged only by the other element 10 to move that element into inoperative position.

In witness whereof, I hereunto subscribe my name this 26th day of March A. D., 1917.

ROBERT MIEHLE.
